United States Patent Office

Des. 183,924
Patented Nov. 18, 1958

183,924

CARD INTERPRETER

Walter Furlani, Endicott, and Myron F. Davis, Jr., Binghamton, N. Y., assignors to International Business Machines Corporation, New York, N. Y., a corporation of New York

Application December 9, 1957, Serial No. 48,833

Term of patent 14 years

(Cl. D26—5)

FIG. 1.

FIG. 2.

Fig. 1 is a perspective view of a card interpreter, embodying our design.

Fig. 2 is a rear elevation view of the same.

The left side of the interpreter is plain. The dominant features of our design reside in those portions shown in full lines on the drawing.

We claim:

The ornamental design for a card interpreter, as shown and described.
